CLAIM

The ornamental design for a wine spray gun, as shown and described.

DESCRIPTION

FIG. 1 is a perspective view of a wine spray gun design showing my new design.

FIG. 2 is a front view of a wine spray gun.

FIG. 3 is a rear view of a wine spray gun.

FIG. 4 is a left side view of a wine spray gun.

FIG. 5 is a right side view of a wine spray gun.

FIG. 6 is a top view of a wine spray gun; and,

FIG. 7 is a bottom view of a wine spray gun.

Broken lines illustrate portions of the wine spray gun that form no part of the claimed design.
